UNITED STATES PATENT OFFICE.

ROBERT K. CLARK, OF EVANSTON, ILLINOIS, ASSIGNOR TO AMERICAN STOVE COMPANY,
OF ST. LOUIS, MISSOURI, A CORPORATION OF NEW JERSEY.

STOVE.

1,285,042.

Specification of Letters Patent. Patented Nov. 19, 1918.

Application filed May 4, 1918. Serial No. 232,551.

To all whom it may concern:

Be it known that I, ROBERT K. CLARK, a citizen of the United States, residing at Evanston, in the county of Cook and State 5 of Illinois, have invented certain new and useful Improvements in Stoves, of which the following is a specification, reference being had therein to the accompanying drawing.

10 This invention relates to improvements in stoves, of that type which are constructed and adapted to receive as fuel what is commonly referred to as "solid alcohol," or "canned heat," which is contained in a can.

15 The stove to which my improvement is applied comprises an open ended drum having suitable supporting feet extending from its lower end and angular-shaped arms projecting from its upper end to support the 20 utensil placed thereon, the contents of which are to be heated or cooked.

My improvement consists in providing a swinging triangular grid or frame adapted to be swung in position to be supported by 25 the angular top arms for receiving a cup or other article too small in diameter to be supported by the arms at the upper end of the drum.

In the accompanying drawings—

30 Figure 1 is a perspective view showing the stove with my improvement in position thereon.

Fig. 2 is a vertical sectional view with my improvement shown in solid lines to receive 35 and support a small article or utensil, and swung back and down in dotted lines when a large utensil is being used.

Referring now to the drawings in which similar reference characters denote the same 40 parts, 1 is an open ended drum or casing made of sheet metal. Attached to the inner side of this drum are three members 2, which are preferably formed from folded sheet metal. These members are attached 45 to the drum by means of rivets 3. The lower ends of these members 2 extend below the drum 1 and are formed into angular-shaped supporting legs 4, which support the drum a suitable distance from the 50 table or other support upon which the stove is placed.

It is well known that the cans (not shown) containing the solid alcohol or canned heat are provided with external 55 grooves extending upward, and these

grooves receive the inwardly bent projections 5, which projections support the can. The can containing the solid alcohol must be inserted into the stove from its upper end, and as a consequence, the upwardly projecting supporting arms 6 cannot have their inner ends 7 extend inward beyond the surface of the members 2. Therefore, the angular supporting arms 6 will not support any article that is smaller in diameter than 60 the can, or properly support any article with a tapered bottom smaller in diameter than the diameter of the can.

My improvement consists in providing a stove with a swinging member 8, which will 65 swing over and rest upon the inwardly extending portions 7 of the supporting arms 6. This member 8 is substantially triangular in plan view, having one end or apex 9 of the angle enlarged and provided with an 70 opening 10 to receive the inwardly extending end 7 of one of the arms 6. The end 7 which passes through the opening 10 is elongated and extends downwardly and outwardly, as shown at 11, which forms a closed 75 triangular supporting end for that arm 9. By reason of this construction, the end 9 of the triangular member 8 is connected with its supporting arm 6 in a manner to prevent 80 its detachment, and to permit it to be swung 85 in a horizontal position, as shown in solid lines in the two figures of the drawings, to receive and support a small utensil, such as a small cup or other article, such as is frequently used in nurseries. The member 8 90 will be swung outward and downward to the positions shown in dotted lines Fig. 2, when a large article is in position on the stove. The two other ends 12 of the triangular member 8 are provided with laterally 95 extending ears 13, which are at opposite sides of the ends 7, and hold the triangular member in position against lateral movement. It will be noticed that the ends 12 are, therefore, substantially of an inverted U-shape to receive the ends 7 of the supporting arms 6, and serve to hold the member 8 against any lateral displacement or movement when it is in a horizontal position to receive and support smaller articles 100 or utensils.

Attention is directed to the fact that the flat end 9 is slightly bent downward, as shown at 14, so that when its loop is interlocked with the loop of the arm 6, the frame 110

8 is permitted to rest in the horizontal position shown, when in use.

Having thus described my invention, what I claim and desire to secure by Letters Patent is—

1. In a stove the combination with an open ended drum provided at its upper end with a plurality of upwardly projecting arms, of a frame having one part swingingly connected with one arm and its free portion adapted to rest on the other arms.
2. In a stove the combination of an open ended drum having a plurality of upwardly projecting arms, of a frame swingingly connected with one of its arms and the free portion of the frame interlocking with the other arms to prevent relative lateral movement between the free part of the frame and the arms engaged thereby.
3. In a stove the combination of an open ended drum having a plurality of upwardly projecting arms of an angular frame having one apex swingingly connected with one of the arms and its other apexes provided with downwardly extending ears interlocking

ing with the other arms for the purpose described.

4. In a stove the combination of an open ended drum, having upwardly projecting arms, one of the arms provided with a loop, an angular frame having one apex provided with an opening interlocking with the said loop, and the other apexes provided with downwardly projecting ears interlocking with the other arms. 35

5. In a stove, the combination of an open ended drum, having three upwardly projecting arms, one of which is provided with a loop, a triangular frame having one apex provided with an opening interlocking with the said loop and the other apexes provided with downwardly projecting ears interlocking with the other arms. 40

In testimony whereof I hereunto affix my signature in the presence of two witnesses. 45

ROBERT K. CLARK.
